Patented Apr. 16, 1957

180,082

ROSE FOR A DOOR LOCK

Glen Holland, Bronxville, N. Y., assignor to The Yale & Towne Manufacturing Company, Stamford, Conn., a corporation of Connecticut

Application November 27, 1953, Serial No. 27,817

Term of patent 7 years

(Cl. D50—6)

Fig. 1.

Fig. 2.

Fig. 1 is a front-elevational view of a rose for a door lock, showing my new design.

Fig. 2 is a perspective view of the rose.

I claim:

The ornamental design for a rose for a door lock, substantially as shown.
